UNITED STATES PATENT OFFICE.

DAVID B. WHISTLER, OF DAYTON, OHIO.

WINDOW.

Application filed June 22, 1926. Serial No. 117,828.

This invention relates to windows having particular reference to double-hung windows in either wood or metal construction.

The objects attained in the invention consist in a window having vertically aligned sash adapted for both vertical and angular adjustments, the angular adjustments being for the purpose of effecting right conditions of ventilation and for convenience and safety in cleaning the windows, having particular reference to outside cleaning, the vertical alignment of the sash and the improved construction resulting also in highly effective weathering of the window without added weather stripping. Incident to these main features are further improvements, as certainty of locking the window upon closing, effectiveness of the locking means to prevent opening of the window from outside, no sticking and no rattling of the sash, no interference with outside screens and, with all, refinements of construction and appearance which make the window an outstanding product.

The present invention is one of a series in the development of the new type of vertically aligned, double-hung, counter-balanced window in wood and metal construction, the particular feature of improvement in this further development consisting of yieldable strips of metal or other suitable material interposed between the sash and the window jambs which serve to space the sash from the jambs, add a finishing bead to the sash, provide a passage for the sash cords or cables, adapt the window in wood construction to the weather variations of wood without affecting the close fitting of the sash or its freedom of operation, and acting to effect practically sealed window as the same is closed.

The improved window is simply constructed, has no complicated mechanism or parts that are likely to get out of adjustment, and is adapted for low cost production being a window for general use in all classes of buildings irrespective of values.

As a residence window, the features which eliminate the dangers and drudgery of window cleaning, the annoyance of rattling, sticking and leaking window; which provide right conditions of ventilation, preventing direct draughts and excluding the weather as the windows are adjusted for ventilation;

which afford greater security and give added architectural distinctiveness to the home, constitute improvements of outstanding importance and fundamental character in modern home building.

In the accompanying drawings, the improved window is illustrated as designed for both wood and metal construction, it being understood that the drawings serve the purpose only of illustrating the principle of the improvement and that it is contemplated in the practice of the invention to use any suitable modifications of the construction here shown as conditions of use and changes in building practice may require.

In the drawings:

Fig. 1 is a vertical sectional view in perspective of the window in wood construction, the window being closed;

Fig. 2 is a vertical sectional view of the window showing the sash in various positions of vertical and angular adjustment;

Fig. 3 is a cross sectional view on line 3—4 of Fig. 1;

Fig. 4 is a cross sectional view on line 3—4 of Fig. 1 showing a modification;

Fig. 5 is an enlarged detail view of Fig. 2;

Fig. 6 is a cross sectional view corresponding to Fig. 3, illustrating the metal window construction;

Fig. 7 is a detail view of the meeting rail construction of both the wood and metal windows;

Fig. 8 is a detail view of the spring tensioned cable pulleys for counter-balancing the sash;

Fig. 9 is a detail view of the lower sash cable connections.

The construction of the window as illustrated in Figs. 1 and 2 consists of opposite jambs 1, head jamb 2, sill 3, trim 4, 5, 6 and 7, upper and lower sash 8 and 9, outer casting 10, spring tensioned sash pulleys 11, sheave pulleys 12, sash cables 13, weather bead 14, screen 15, meeting rail 16, meeting rail drip strip 17, lower sash guides 18—22 and the flexible jamb strips 19.

The particular improvement of the window as herein set forth consists of the yieldable metal strips 19, best shown in Fig. 3 and in a modified form in Fig. 4, the strips 20, as shown in Fig. 4, being made of resilient material, as rubber, or fabricated material, as felt. The strips made in any suit-

able material are secured to the opposite jambs, between the side edges of the sash and the jambs, being extended the full height of the window opening and applying to both sash.

The yieldable elements 19—20, in either form have the effect of spacing the sash from the jambs, thus causing a dead air space 21 to be formed between the sash and the jambs which is an important factor in the weathering of the window as will presently be described. Lower sash guides 22 are set in the spaces 21, the guides being extended upward from the sill into the plane of the upper sash as indicated at 23 in Fig. 2. The opposite side edges of the lower sash are connected to the guides by links 24 connected pivotally to the sash as indicated at 25 and also pivotally to shoes 26 as indicated at 27 the shoes being operable slidably under frictional resistance in the guides.

The shoes 26 afford a suitable connection for the lower ends of the sash cables (see Fig. 9) and coat with the spring tensioned counter-balancing pulleys 11 to hold the lower sash yieldingly but with sufficient firmness in any position of angular adjustment to prevent swaying of the sash, thus adapting the sash for a wide range of adjustment for ventilating, the full angular movement of the sash being through an arc of 90°.

For adjusting the lower sash vertically, the sash is opened at the meeting rails and is drawn inward until its top edge clears the upper sash, the lower portion of the sash being then moved inward which acts to dispose the sash in a vertical plane in position to be moved upward between the upper sash and the sash guides 18 which are provided with latching apertures 28 adapted to be engaged by the latching bars 29 operable in the meeting rail 16, means being thus provided for supporting the sash selectively in variable positions of vertical adjustment. In like manner the latch bars are adapted to coat with apertures 30 in the opposite jambs for locking the closed window and with apertures 31 for adjusting the lower sash for normal ventilation, the apertures being reinforced by jamb face plates 32.

The upper sash is also adapted for both vertical and angular adjustments. To move the upper sash downward, and lower sash is first adjusted inward out of the plane of the upper sash, the upper sash being then free, except as to the action of the counter-balancing connections thereon, to be lowered and also to be moved inward at an angle over the outer face of the lower sash (see Fig. 2). The sash cables 13, as here shown are connected direct to the upper sash as indicated at 13^a. It will be obvious, however, that sash connections 24—26 may also be

used for connecting the upper sash to the 65 vertical guides 22 in a manner similar to the connection of the lower sash, the guides being made suitably longer. Greater freedom of movement of both sash is obtained, however, by connecting the sash cables direct to the upper sash as here shown.

The spring-tensioned, counter-balancing sash pulleys are assembled in a single unit 70 consisting of a supporting bracket 33 adapted to be located in the head of the window 75 intermediate the opposite jambs, the head board of the trim being removable to afford convenient access to the pulleys for installing the windows and for making any subsequent adjustments. Each of the pulleys 34 is tensioned opposite to the weight of the sash by a coiled spring 35 and is adapted to have the opposite sash cables for one of the sash connected thereto on opposite sides of the pulley center so that the cables will be 80 wound and unwound on the pulleys equally one with the other. Means consisting of a sleeve 36 to which the inner end of spring 34 is connected, an adjusting collar 37 being part of the sleeve, and a pin 38 for securing the collar relative to the pulley shaft 39 are provided for regulating the tension of the spring.

While the spring tensioned pulleys are 95 here shown as the preferred means for counter-balancing the sash, it will be obvious that the construction of the window is suitable for using ordinary sash weights.

The strips 19 are adapted to be made of any suitable material, as spring tempered 100 sheet metal of the required gauge to render the mouldings flexible to the lateral pressure of the sash, and thus adaptable to compensate for the variations in the dimensions of the sash, having particular reference to the 105 contraction and expansion of wood sash under the influence of the weather, as well as for structural variations, this latter condition applying also to the metal windows. Whatever degree of accuracy is maintained 110 in the construction of the windows whether wood or metal, more or less variation in the alignment of the sash and frames will result in installing the windows. All such normal variations of whatever character will be 115 compensated for by the flexible element interposed between the sash and frame and tight fitting and free operating conditions will be obtained in the first installation of the windows and will be maintained thereafter.

The strips 19—20 are preferably extended sufficiently inwardly beyond the edges of the sash to form an unbroken finishing bead along the inner opposite edges of both sash, the frictional contact with the sash being wholly within the plane of the sash. The shape of the interposed element in cross sec-

tion is adaptable for various modifications from that shown in the illustrations in Figs. 3 and 4.

- The improved construction as herein shown and described results in double weathering of the window,—outer and inner weathering. The outer weathering is effected by pressure between both sash and the outer stops or weather beads 14 when the window is closed, the outward pressure of the sash resulting from engagement of the tapered ends 29^a of latch bars 29 with apertures 30 in plates 32, the bars being pressed home in the apertures by the finger piece 40. 10
- 15 The upper sash is forced outward by the pressure of the lower sash at the meeting rails which has the further effect of forcing the lower inner edge of the lower sash against the outwardly turned shoulder 41 of 20 the window sill.

The outer weathering of the window is in itself highly effective. The means of its accomplishment are also effective to prevent opening of the window from outside and to 25 prevent rattling of the sash when the window is closed.

The inner weathering is a further feature of the flexible elements 19—20, or their equivalent, which practically seal the inner 30 side edges of both sash. The manner of interposing these elements between the sash and jambs, as shown and described, or in modified form to the same effect, also provides the dead air spaces 21 which act to 35 prevent air currents through the outer and inner weathering. The meeting rail construction, as best shown in Fig. 1, also comprises inner and outer weathering consisting of the meeting rail 16, drip strip 17 and a 40 dead air space 42 formed between the sash.

Spacing of the sash from the jambs as herein shown serves to prevent marring of the jambs as the sash are adjusted for opening the window, the sash being entirely out 45 of engagement with the jambs in both the angular and vertical adjustments of the same.

It will be observed that the sash cables do not move with the lower sash in the angular 50 adjustments of the same, the cables being at all times confined within the strips 19. The cables are connected to shoes 26 by means of knots 43 formed in the ends of the cables and slots 44 formed in the upper 55 pivot studs 44, the cables being slipped into the slots free to permit of readily disconnecting the same for removing the sash.

A detail of the invention as applied to a metal window in one form is illustrated in 60 Fig. 6, the detail being a cross sectional view through a jamb. As here shown, the construction consists of inner and outer jamb members 45—46, these parts having the stops 47 for the sash 48 formed integrally therewith, the stops being channel shaped in

cross-section to form dead air spaces 49 between the sash and the jambs. The inner weathering element 50, as here shown, consists of a formed strip of metal which is yieldable to lateral pressure of the sash. The 70 sash is connected to the jambs by guides 51, slideable friction shoes 52 and links 53 in a manner similar to the construction of the wood, the sash cables 54 being connected to shoes 52. 75

Having described my invention, I claim:

1. A window including in combination, upper and lower, vertically aligned sash supported for vertical and angular adjustments, outer stops for the sash and a member yieldable to lateral pressure interposed between the opposite edges of both sash and the window jambs, said members coacting with the outer stops to effect weathering of the window. 80

2. A window including in combination, upper and lower, vertically aligned sash supported for vertical and angular adjustments, outer stops for the sash and a member yieldable to lateral pressure of the sash interposed between the opposite edges of both sash and the window jambs and exposed on the inner edges of the sash, said members coacting with the outer stops to effect weathering of the window. 85

3. A window including in combination, upper and lower, vertically aligned sash supported for vertical and angular adjustments, outer stops for the sash and a member yieldable to lateral pressure of the sash interposed between the opposite edges of both sash and the window jambs and forming finishing beads along the inner edges of the sash, said members coacting with the outer stops to effect weathering of the window. 90

4. A window including in combination, upper and lower, vertically aligned sash, supported for vertical and angular adjustments, outer stops for the sash and a member yieldable to lateral pressure of the sash, secured to the window jambs between the opposite edges of both sash and the jambs. 100

5. A window including in combination, upper and lower, vertically aligned sash, supported for vertical and angular adjustments, outer stops for the sash and a member responsive to lateral expansion and contraction of the sash interposed between the opposite edges of both sash and the window jambs, said members coacting with the outer stops to effect weathering of the window. 110

6. A window including in combination, upper and lower, vertically aligned sash spaced from the window jambs and supported for vertical and angular adjustments, weather beads outwardly of the sash, a member yieldable to lateral pressure of the sash interposed between the opposite edges of both sash and the jambs, and connections 120

130

for counter-balancing both sash extended in said spaces between said members and the weather beads.

7. A window including in combination, 5 upper and lower, vertically aligned sash spaced from the window jambs and supported for vertical and angular adjustments, weather beads fixed outwardly of the sash, a member yieldable to lateral pressure of 10 the sash interposed between the opposite edges of both sash and jambs, and connections for counter-balancing the sash and guides for the lower sash extended in said spaces between said members and the weather 15 beads.

8. A window including in combination, upper and lower, vertically aligned sash spaced from the window jambs, and supported for vertical and angular adjustments, 20 weather beads fixed outwardly of the sash, a member yieldable to lateral pressure of the sash interposed between the opposite edges of both sash and the jambs, and connections for counter-balancing the sash and 25 guides for the lower sash extended in said spaces and frictional members slidable in the guides for controlling the sash.

9. A window including in combination, upper and lower, vertically aligned, sash 30 supported for vertical and angular adjustments, weather beads fixed outwardly of the sash, channel members interposed between the sash and jambs, said members being fixed to the jambs, shaped to close the space be-

tween the sash and jambs, having free edges 35 thereof turned into engagement with the sash and yieldable to lateral pressure thereof, said members coacting with the outer stops to effect weathering of the window.

10. A window including in combination, 40 upper and lower, vertically aligned sash supported for vertical and angular adjustments, weather beads fixed outwardly of the sash, and strips of metal secured to the jambs adjacent the edges of both sash, having 45 the free edges thereof turned upward from the jambs in to engagement with the inner edges of the sash, yieldable to lateral pressure of the sash, said members coacting with the outer stops to effect weathering of 50 the window.

11. A window including in combination, upper and lower, vertically aligned sash supported for vertical and angular adjustments, 55 weather beads arranged outwardly of the sash, means operable manually upon closing the window for effecting contact of the sash under pressure with the weather beads, and elements interposed between the sash and the window jambs yieldable to lateral 60 contraction and expansion of the sash, acting to maintain frictional contact with the side edges of the sash, said member coacting with the outer stops to effect weathering of 65 the window.

In testimony whereof, I affix my signature.

DAVID B. WHISTLER.
